UNITED STATES PATENT OFFICE

WILLIAM DOW HARVEY, OF MACOMB, ILLINOIS, ASSIGNOR TO AMERICAN STEEL PRODUCTS CO., OF MACOMB, ILLINOIS, A CORPORATION OF ILLINOIS

COAL-BURNING BROODER

Application filed October 17, 1927. Serial No. 226,652.

My invention relates to brooders for use with solid fuel (such as coal, coke or wood) and in some of its general objects aims to provide a simple and relatively inexpensive 5 brooder affording the following advantages:

(1) An automatic regulation of the heat by a simultaneous control of the air supply through the grate of the heater and of the draft up the flue.

10 (2) A speedy checking of an unduly high temperature under the hover by the withdrawal of the hottest air.

(3) A check-draft arrangement which will permit a readily removable baffle member 15 to produce the check draft chamber of the brooder heater.

Further and more detailed objects will appear from the following specification and from the accompanying drawings, in which 20 drawings—

Fig. 1 is a fragmentary view of a brooder embodying my invention, showing a front elevation of the heater and draft-regulating means, together with a fragmentary central and vertical section of the hover supported by the heater.

Fig. 2 is a fragmentary plan view of the same brooder.

Fig. 3 is a view taken at right angles to Fig. 1, comprising a side elevation of the same heater, taken from the left side of Fig. 1, and a fragmentary central and vertical section of the hover.

Fig. 4 is an enlarged plan view of the heater and of a part of the check draft damping arrangement, with a portion of the heater cut away to show portions of the baffle member which co-operates with side wall and top portions of the heater body to form a check draft chamber.

Fig. 5 is a perspective view of the baffle member of the heater.

Fig. 6 is an enlarged vertical section, taken along the line 6—6 of Fig. 3 to show the check draft arrangement.

Fig. 7 is an enlarged vertical section along the line 7—7 of Fig. 3 to show the draft control for the supply of air through the grate.

Fig. 8 is a fragmentary elevation of the 50 heater body taken from the line 8—8 of Fig.

6 to show the shape of the check draft aperture and the outer end of the baffle member.

In the illustrated embodiment, the heater body comprises a bottom section 1 supporting an ashpit section 2, which latter section supports both the grate 3 and the main body section (or combustion chamber section) 4, all of these sections being shown as approximately square, although their horizontal shape is immaterial. The ashpit section 2 has 60 at its front a door 5 which can be detached both for removing the ashes and for securing an intense draft when the fuel is first lighted, but this door is closed when the fire is well started, as the air supply for the grate is then 65 taken through an aperture 6 in the rear wall of the ashpit section of the heater body.

The top 7 of the heater body, which is here shown as integral with the side walls of the main body section, is provided with a flue 70 pipe collar 8, desirably near but slightly spaced from the rear side wall of the heater body, and is also provided with a fuel inlet which is normally closed by a lid 9. Adjacent to the flue pipe collar, and desirably at the 75 same side of the heater with the air supply aperture 6, the heater body is provided near its top with an aperture 10 opening into a check draft chamber 11 which underhangs the flue aperture 8 and which has a restricted 80 connection to the combustion chamber section of the heater.

The check draft chamber 11 has three of its sides formed by upper side wall portions of the heater body and has a part of the heater 85 top 7 as its own top, while the fourth side wall and the bottom of this check draft chamber are respectively formed by the vertical web 12 and the horizontal web 13 of a baffle member which is pictured separately in Fig. 5. This 90 baffle member has its vertical web 12 in alignment with the part of the fuel inlet nearest to the flue aperture and has this vertical web provided adjacent to its upper end with oppositely directed fingers 14 which seat in 95 notches formed in the upper edge of the two opposite side walls of the heater body. The baffle member also has the free end of its horizontal web 13 provided with a projection 16 extending into the check draft aperture 10, 100

so that this end of the baffle member is supported by the lower wall of the aperture 10, so that this aperture wall co-operates with the bottoms of the finger-supporting notches in the heater body in affording the entire support for the baffle member.

The vertical web 12 of the baffle member desirably extends close to the front and rear walls of the heater, while the horizontal web 13 is formed so as to restrict the passage of the smoke and combustion gases from the combustion chamber 18 to the check draft chamber, for which latter purpose I am showing the horizontal web 13 sufficiently narrow to afford smoke passage spaces 15 between its front and rear ends and the heater body. In Figs. 4 and 5 I am also showing these smoke passages 15 as supplemented by perforations 17 in the horizontal web 13, but these perforations may be omitted if the horizontal web is correspondingly narrowed to increase the size of the smoke passages, or the horizontal web may be widened to reach close to the front and rear walls of the stove while the perforations 17 are correspondingly increased in size to afford the entire connection between the combustion chamber 18 of the heater and the check draft chamber. With each of these obvious variations, the projection 16 preferably corresponds in width to the check draft aperture 10 into which it extends.

To control the drafts through the apertures 6 and 10 automatically, I provide two pivoted dampers 20 and 21, both connected to a thermostatic mechanism supported by the ashpit section of the heater body. For the air supply control, I cast a pair of spaced brackets 22 on the side of the ashpit body section 2, each of which brackets has at its top an upwardly open notch 23 disposed above the air supply aperture 6. Then I provide an air supply damper 20 having two pintles 24 journaled respectively in the bracket notches 23, this damper being shaped so that it can entirely close the aperture 6, and I also provide this damper 20 with an arm 25 projecting rearwardly from its lower portion.

The check draft damper 21 has a web 26 projecting rearwardly from its lower end and has at the rear end of this web a pair of pintles 27 which are journaled in the legs of a U-shaped pivoting bracket 28 bolted to the back of the heater body adjacent to the check draft aperture. This check draft damper also has a rearwardly projecting arm 29, and the bight of the U-shaped bracket 28 is formed so that it can engage the arm 29 to limit the outward swinging of the damper.

For the thermostatic mechanism, I am showing a stationary bracket 30 secured to the ashpit section of the heater, from the outer end of which bracket a lever 31 is suspended by a bolt 32, and am showing ther-

mally expansible wafers 33 interposed between the bracket 30 and the lever 31 so that the expansion of the wafers will swing the inner end of the lever downwardly by rocking the lever about the lower nut end of the bolt 32. This inner lever end is connected by a link 34 with the arm 25 of the air supply damper, and that arm is connected by a link 35 with the arm 29 of the check draft damper.

With the two dampers thus supported, gravity will continually tend to move both dampers to their closed positions, while the weight of the lever 31 will tend to move them in the opposite direction. By making the upper damper heavier than the lower one—for which purpose I show a weight 36 on the upper damper near its inner edge—I can cause this to overbalance the weights of the lever 31 and the lower damper; and by suitably proportioning the lengths of the links 34 and 35, I can cause the upper damper to be in its closed position and the lower damper in its open position when the thermostatic wafers are relatively cold.

For the hover of my brooder, I desirably employ a knock-down construction, comprising sectors 37 which together form the upwardly tapering main portion of the hover and which are bolted at their upper ends to a downwardly flaring peripheral flange 38 of a hover canopy. This hover canopy includes a top 39 which is perforated so that the flue pipe collar 8 and the fuel lid 9 can project through it, thereby permitting a considerable portion of the generally horizontal canopy top to seat flatwise on the top 7 of the heater body, as shown in Fig. 2. By shaping the perforation 40 in the canopy top so that the perforation closely fits the flue pipe collar 8 and the fuel lid, I cause this perforation to center the hover on the heater, thus permitting me to use a canopy top extending radially beyond the heater for a considerable distance. When my brooder is in use, hot air collects in this upper canopy portion. With the check draft damper 21 pivoted at its bottom, this damper opens widest at its top, so that air enters the heater through the check draft opening most easily from above the damper. To facilitate this taking of the uppermost and hence hottest air from the interior of the hover, I preferably emboss the portion of the canopy top which overhangs the entire damper, and the raised portion 41 provided for this purpose may extend up to the flue pipe collar as shown in Figs. 1 and 2. This raising of this portion also affords added clearance for the upper edge of the check draft damper, thereby permitting me to employ a check draft chamber of relatively small height. By using a radially projecting canopy top, I also permit air to circulate readily around the stove, so

that the opening of the check draft damper will withdraw the hottest (and hence least fresh) air, while the companion damper 20 controls the more fresh air for supply through the grate of the heater.

5 In practice, the entire canopy top can readily be formed of sheet metal, desirably with a cylindrical portion 41 between the flange 38 and the top portion, as the lateral 10 wall of the hot air chamber of the canopy, so that I avoid the need of a heavy cast iron collar as heretofore employed with the hovers of coal fired brooders. Hence the entire hover may be quite light and easily lifted 15 off the heater by a bail 42 for more convenient access to the ashpit. But the hover need not be shifted in position for refueling the heater, or even for cleaning the check draft chamber, since the mere lifting of the 20 lid permits a replenishing of the fuel and also allows the baffle member to be removed for cleaning.

25 By simultaneously controlling the two dampers, I secure a sensitive regulation. To make this responsive to the average of the temperature adjacent to the chicks, I desirably position the thermostatic wafers near the floor and at a considerable distance from the heater but under the hover. However, I 30 do not wish to be limited in this respect, nor to other details of construction and arrangement above disclosed, since many changes might obviously be made without departing either from the spirit of my invention or 35 from the appended claims.

I claim as my invention:

1. A brooder for use with solid fuel, comprising a heater having a lateral check draft opening near its top, and having an upper 40 fuel feed opening and an upper flue collar; a lid for the feed opening; a hover having a top seated upon the top of the heater and having a perforation exposing the said lid and the flue collar, the perforation wall being 45 formed for laterally engaging upper stove portions so as to center the hover on the heater; and a damper movable into and out of positions in which it closes the said opening, the damper being pivotally supported 50 by the heater on an axis adjacent to the lower edge of the said opening and arranged for having the upper end of the damper swing away from the heater during the opening 55 movement of the damper; the hover having a raised portion overhanging the damper and serving as a hot air chamber for accumulating the hottest air within the hover, 60 whereby the opening of the damper will admit air to the heater from the said hot air chamber.

2. A brooder for use with solid fuel, comprising a heater body having a lower air 65 supply aperture and a higher check draft ap-

erture in the same side of the heater; a damper for the check draft aperture pivotally connected to the said heater side on an axis near the lower edge of the damper; a second damper pivoted on an axis near its 70 upper edge to the said heater side and controlling the lower air supply aperture; a thermostatic mechanism including a pivoted lever and thermally actuatable means for moving the lever downwardly in response to a 75 rise in temperature; means connecting the lever with both dampers whereby downward movement of the lever moves the first named damper outwardly of the heater and moves the second damper towards the heater; means 80 associated with the first named damper for continually tending to move the latter toward the heater, the said means being such as to overbalance the weight of the lever and of the second damper; and a hover having 85 its top resting upon and in close fitting relation to the top of the said heater, the hover extending freely above and outwardly beyond the first named damper and having its lower edge approximately at the height of 90 the second damper.

3. A coal-burning brooder comprising a heater having its top provided with a fuel feed opening and a flue opening, the heater having a check draft chamber underhanging the flue opening and having a lateral inlet to the chamber; a hover supported by the said top and surrounding the upper portion of the heater to afford a brooder chamber connected to the check draft chamber by the said inlet, the top of the hover including a part thereof spaced upwardly from the damper and the top of the heater so that the brooder chamber includes an upper brooder chamber portion above the top of the heater, and a damper under the hover for controlling the said inlet, the damper being movable from a closure position in which it bears against a side of the heater to an open position in which it diverges upwardly from the said side so as to admit air to the check draft chamber from the said upper brooder chamber portion.

4. A coal-burning brooder comprising a heater having its top provided with a fuel feed opening and a flue opening, the heater having a check draft chamber underhanging the flue opening and having a lateral inlet to the chamber; a hover supported by the said top and surrounding the upper portion of the heater to afford a brooder chamber connected to the check draft chamber by the said inlet, the top of the hover having a perforation exposing the fuel feed opening and the flue opening, the said hover top resting upon the top of the heater but having a raised portion overhanging the said inlet and extending substantially from the flue opening for some distance radially outward beyond 125 130

the top of the heater to permit the accumulation of hot air within the hover above the top of the said inlet, and a damper controlling the said inlet and opening upwardly for admitting hot air from above the inlet.
